UNITED STATES PATENT OFFICE

1,998,328

AUTOMATIC HAND RIVETING MACHINE

Roxton C. McKinnie, Detroit, Mich.

Application September 22, 1933, Serial No. 690,550

14 Claims. (Cl. 218—19)

This invention relates to riveting machines and particularly to that type of machine adapted to use split rivets.

The principal object of the invention is the provision of an improved device of the character indicated which can readily be used to fasten together the exposed edges of sheet roofing material as described in my co-pending application, Serial Number 667,963.

Another object of the invention is the provision of an automatic portable hand riveting machine which can be efficiently operated with a minimum of physical exertion.

Another object of the invention is the provision of a device of the character referred to which is capable of attaching a plurality of split rivets in succession without the necessity of reloading.

Another object of the invention is the provision of a device of the character referred to having a full floating jaw mechanism adapted to firmly grip the rivet and maintain it in alignment while it is being forced through the material to be riveted.

Another object of the invention is the provision of a riveting machine which is economical to manufacture, simple in construction and easy to operate.

With these and other objects in view, it will be seen that the invention consists of certain novel features of design and construction and in the particular combination and arrangement of parts, all of which will be better understood after a careful examination is made of the following specifications, reference being had at the same time to the accompanying drawing in which:

Fig. 1 is a side elevational view of the device embodying my invention with parts broken away to illustrate the relative position of the several elements.

Fig. 2 is a front elevational view of my improved riveting machine.

Fig. 3 is a sectional view taken on line 3—3 of Fig. 1.

Fig. 4 is a sectional view taken on line 4—4 of Fig. 3.

Fig. 5 is a sectional view taken on line 5—5 of Fig. 3.

Fig. 6 is a sectional view taken on line 6—6 of Fig. 5.

Fig. 7 is a sectional view taken on line 5—5 of Fig. 3.

Fig. 8 is a sectional view taken on line 8—8 of Fig. 7.

Fig. 9 is a sectional view of a completely stapled split rivet.

Referring now more particularly to the drawing it will be seen that the principal working parts of the device embodying my invention are housed within and carried by a body portion 12, which is preferably made of aluminum or other light material cast in such manner as to form, at one end, a horizontally disposed handle 13, having a cross section substantially as shown at 10 14, and at the other end an angularly disposed portion 15 terminating in a clevis 16.

An operating lever 17 is mounted within the clevis 16 upon a fulcrum pin 18, and is permitted to make substantial downward movement from 15 the position as shown in Fig. 1, whereas its upward movement from the same position is limited by the head 19, which is adapted to contact the angular portion 15 of the body 12 to form a stop. The limited upward movement of 20 the lever 17 permits the device to be carried about in a substantially horizontal position by simply grasping the operating lever 17 instead of having to grasp both the handles 13 and 17. The free end of the lever 17 has a cross section simi-

25 lar to the cross section of the handle 13 but inverted. Press fitted into the underside of the lever 17 is a flat headed stud 20, preferably made of steel or other hard material, and adapted to act as a bearing surface between the lever 17 30 and the plunger 21, which is slidably mounted in a vertical passageway 22 positioned in the body 12. Within the passageway 22 is a spring 23, which is adapted to exert pressure against the shoulder 24 of the plunger 21 to normally main-

35 tain the plunger 21 in the extended position as shown in Fig. 1. A bushing 25 is press fitted into the upper end of the passageway 22 and serves 30 as a guide for the plunger 21 and a stop to limit its upward movement. The plunger 21 has a 40 reduced portion 26 adapted to travel in a smaller passageway 27 which extends downwardly from the bottom of the passageway 22. Centrally formed on the lower extremity of the reduced portion 26 of the plunger 21 is a seat 28, which is 45 adapted to engage a recess 29 formed in the head of the rivet 30 and serves the purpose of assisting to hold the rivet 30 in an upright position during its downward movement as hereinafter described.

40 A vertical slot 31 is machined in the body portion 12 and is of sufficient size to receive a flat spring 32, one end of which spring 32 is secured to a stud 33 by means of a screw 34. The stud 33 passes completely through the body 12 and 50

55 45

50

55

55

has a groove in one end capable of receiving a screw driver so that it can be turned to adjust the tension on the spring 32. A set screw 35 is adapted to secure the stud 33 in its bearing when the desired tension is obtained on the spring 32. The free end of the spring 32 is fixed to the rivet feed slide 36 by means of a knurled knob 37.

Extending between depending flanges formed on the lower portion of the body 12 and secured thereto by means of screws 38, is a rivet magazine 39, which is provided with a full length longitudinal slot 40 adapted to receive a plurality of rivets placed side by side in a vertical position. Plates 41 and 42 are secured to the top 15 of the rivet magazine 39 by means of screws 43, and are adapted to maintain the rivets in alignment and serve as retaining elements and guides for the slide 36. The forward travel of the slide 36 is terminated by a stop plate 44 which is secured to the magazine 39 by screws 45.

One of the features of my invention is the full floating jaw arrangement which I will now describe. It is this feature of the invention which permits the rivet to be held firmly in a vertical position while it is being forced through the heavy material to be riveted. To effect the full floating jaw arrangement referred to, I provide a U-shaped member 46 which I secure to the end of the rivet magazine 39 by means of screws 47. The U-shaped member 46 serves as a housing and a guide for the jaws 48 and 49, which are adapted to reciprocate vertically therein. The jaws 48 and 49 are normally held closed by means of two concealed compression springs 50 and 51, which in turn are held in place by means of a bolt 52 which is provided, at one end, with a head 53 and at the other end with a cotter pin 54, as shown in Fig. 4. The jaws 48 and 49 are normally held in retracted vertical position, as shown in Fig. 2, by means of tension springs 55 and 56 which are securely fastened to spring studs 57 and 58, which are screwed into the sides of the body 12, and to the spring studs 59 and 60 which pass through vertical slots 61 and 62 in the U-shaped member 46 and are screwed into the jaws 48 and 49. To insure perfect vertical alignment of the jaws 48 and 49, a gib 63 is formed on the inner side of the U-shaped member 46 and a gib 64 is formed on the end of the rivet magazine 39, said gib 63 and 64 being adapted to engage vertical grooves formed on the front and back, respectively, of the jaws 48 and 49.

A semi-cylindrical groove 65 is formed on each jaw 48 and 49, which grooves together comprise a vertical passageway through the jaws 48 and 49 to permit the passage there-through of the reduced end 26 of the plunger 21. Concentric with the groove 65 a ring-shaped groove 66 is machined in each jaw 48 and 49. The last named groove 66 is normally in direct alignment with the rivet head passageway 40 extending through the rivet magazine 39, and is of such depth and contour as to engage the head of rivet 30. When such engagement is had, the rivet 30 is securely held in the jaws 48 and 49 with the shank of the rivet 30 extending downwardly through the jaws, as shown in Fig. 5, in which position the rivet 30 is ready to be struck by the reduced end 26 of the plunger 21. It will be noted that when the rivet is struck by the plunger 21, the jaws 48 and 49 are also actuated downwardly for the reason that the head of the rivet 30 still reposes in the groove 66 and is being firmly gripped by the jaws 48 and 49. (If for any reason a rivet should not lodge in the jaws 48 and 49, or should the magazine 39 become

empty, it would be impossible to actuate the jaws 48 and 49, and in that event the reduced end 26 of the plunger 31 would travel clear through the jaws 48 and 49.) The jaws 48 and 49 holding the rivet continue their downward movement until the rivet 30 is forced well through the material to be riveted. To release the rivet 30 from the jaws 48 and 49 at the desired instant, I provide an expansion cam mechanism between the jaws 48 and 49, which consists of a cam stud 67, having an enlarged conical head 68, which is securely screwed into the under side of the body 12 near the front, and extends downwardly through passageways 69 and 70 formed by semi-cylindrical grooves machined in each jaw. The upper portion 69 of the 15 passageway, formed as aforesaid, is of sufficient diameter to accommodate the shank of the cam stud 67. The lower portion 70 of the passageway so formed is graduated in diameter and is adapted to accommodate the conical head 68 of the cam stud 67 to form a perfect cam surface therefor. As the jaws 48 and 49 continue to travel downwardly, the cam surface 70 engages the head 68 of the cam stud 67, causing the jaws 48 and 49 to separate and release the rivet 30, as indicated in 25 Fig. 7. When the rivet is released, the jaws 48 and 49 are retracted to their normal positions, as shown in Figs. 1 and 2, and the rivet 30 is forced the rest of the way through the material and is clinched over on the anvil 71 which is secured to 30 the under side of the rivet magazine 39 by screws 72, or other suitable means. The whole device is stabilized while in use by a cross member 73 which is attached to the under side of the free end of the riveting magazine 39 by any suitable means. 35

To operate the device the feed magazine 39 is filled with the proper type of split rivets 30 and the feed slide 36, which is normally under constant tension of spring 32 is placed in position so that the feed slide 36 urges the rivets toward the jaws 48 and 49. It will be remembered that the feed slide 36 travels in the longitudinal slot 40, which also carries the rivets to be fed into the jaws 48 and 49. The slot 40 is in direct alignment with the grooves 66 formed in the jaws 48 and 49. 45 The grooves 66, together with the grooves 65, also formed in the jaws 48 and 49, make a recess in the jaws of the size and shape of a rivet, and permit the introduction of a rivet into the jaws 48 and 49, which are normally closed while in the position 50 of rest, as shown in Fig. 1. Handles 13 and 17 are then grasped with one hand only, forcing the plunger 21 against the head of the rivet 30, which rivet 30, together with the jaws 48 and 49, are forced downwardly to the position indicated in 55 Figs. 5 and 6. By this time the prongs of the rivet 30 have entered the material to be riveted, centralizing the end of the rivet while the head of the rivet is still between the jaws 48 and 49. If further pressure is then applied to the rivet, the 60 jaws 48 and 49 are forced against the conical head 68 of the cam stud 67, causing the jaws 48 and 49 to separate and release the rivet 30, permitting the same to be pushed through and clear of the jaws 48 and 49, as shown in Fig. 7. During 65 this operation the succeeding rivet is retained in the magazine 39 because the head of the succeeding rivet rides up against the jaws 48 and 49 and is prevented from entering said jaws until the slot 66 in the jaws 48 and 49 becomes aligned with 70 the rivet head passageway of the slot 40. Instantly upon the rivet 30 leaving the jaws 48 and 49, the jaws are horizontally and vertically returned to their original position by the spring members 50 and 51 and 55 and 56, respectively. 75

The plunger 21, however, is still further depressed to drive the rivet 30 through the material and against the anvil 71 to complete the stapling process. When the lever 17 is released, it, together with the plunger 21, will be returned to its original position, as shown in Fig. 1, by the spring 23. When the plunger 21 and the jaws 48 and 49 again return to their original positions, a second rivet can enter the jaws and the cycle may be 10 repeated until the rivets are exhausted from the said magazine.

Having described my invention, what I claim and desire to secure by Letters Patent is:

1. In a riveting machine, adapted to work on heavy materials, the combination of a body portion having a handle formed at one end thereof and an angularly disposed clevis formed at the other end thereof, a lever fulcrumed in said clevis, a plunger in said body portion adapted to be actuated by said lever, a pair of reciprocating jaws in said body adapted to hold a rivet and to be actuated by said plunger while said rivet is being forced into the material to be riveted.

2. In a riveting machine, adapted to work on heavy materials, the combination of a body portion having a handle formed at one end thereof and an angularly disposed clevis formed at the other end thereof, a lever fulcrumed in said clevis, a plunger in said body portion adapted to be actuated by said lever, a pair of reciprocating jaws in said body adapted to hold a rivet and to be actuated by said plunger, and a rivet magazine secured to said body, said magazine having a feed slot in alignment with a recess formed in said jaws when said jaws are in their position of rest.

3. In a riveting machine, adapted to work on heavy materials, the combination of a body portion having a handle formed at one end thereof and an angularly disposed clevis formed at the other end thereof, a lever fulcrumed in said clevis, a plunger in said body portion adapted to be actuated by said lever, a pair of reciprocating jaws in said body adapted to hold a rivet and to be actuated by said plunger, a rivet magazine secured to said body, said magazine having a feed slot in alignment with a recess formed in said jaws when said jaws are in their position of rest, a feed slide for said rivet magazine, and resilient means for urging said feed slide toward said jaws.

4. In a riveting machine, adapted to work on heavy materials, the combination of a body portion having a handle formed at one end thereof and an angularly disposed clevis formed at the other end thereof, a lever fulcrumed in said clevis, a plunger in said body portion adapted to be actuated by said lever, a pair of reciprocating jaws in said body adapted to hold a rivet and to be actuated by said plunger, a rivet magazine secured to said body, said magazine having a feed slot in alignment with a recess formed in said jaws when said jaws are in their position of rest, a feed slide for said rivet magazine, resilient means for urging said feed slide toward said jaws, and means for adjusting and maintaining tension on said resilient means.

5. In a riveting machine, adapted to work on heavy materials, the combination of a body portion having a handle formed at one end thereof and an angularly disposed clevis formed at the other end thereof, a lever fulcrumed in said clevis, a plunger in said body portion adapted to be actuated by said lever, a pair of reciprocating jaws in said body adapted to hold a rivet and to be actuated by said plunger, and resilient means

adapted to maintain said plunger and said lever in normally extended position.

6. In a riveting machine, adapted to work on heavy materials, the combination of a body portion having a handle formed at one end thereof and an angularly disposed clevis formed at the other end thereof, a lever fulcrumed in said clevis, said lever having a depending head adapted to limit its upward movement, a plunger in said body portion adapted to be actuated by said lever, 10 a pair of reciprocating jaws in said body adapted to hold a rivet and to be actuated by said plunger.

7. In a riveting machine, adapted to work on heavy materials, the combination of a body portion having a handle formed at one end thereof and an angularly disposed clevis formed at the other end thereof, a lever fulcrumed in said clevis, a plunger in said body portion adapted to be actuated by said lever, a pair of reciprocating jaws in said body adapted to hold a rivet and to be actuated by said plunger, said jaws having resilient means adapted to urge said jaws together.

8. In a riveting machine, adapted to work on heavy materials, the combination of a body portion having a handle formed at one end thereof and an angularly disposed clevis formed at the other end thereof, a lever fulcrumed in said clevis, a plunger in said body portion adapted to be actuated by said lever, a pair of reciprocating jaws in said body adapted to hold a rivet and to be 25 actuated by said plunger, and resilient means for normally urging said jaws upwardly.

9. In a riveting machine, adapted to work on heavy materials, the combination of a body portion having a handle formed at one end thereof and an angularly disposed clevis formed at the other end thereof, a lever fulcrumed in said clevis, a plunger in said body portion adapted to be actuated by said lever, a pair of reciprocating jaws in said body adapted to hold a rivet and to be 30 actuated by said plunger, and means for maintaining said jaws in vertical alignment.

10. In a riveting machine, adapted to work on heavy materials, the combination of a body portion having a handle formed at one end thereof and an angularly disposed clevis formed at the other end thereof, a lever fulcrumed in said clevis, a plunger in said body portion adapted to be actuated by said lever, a pair of reciprocating jaws in said body adapted to hold a rivet and to 45 be actuated by said plunger, and a cam positioned between said jaws adapted to open said jaws while said jaws are being so actuated.

11. In a riveting machine, adapted to work on heavy materials, the combination of a body portion having a handle formed at one end thereof and an angularly disposed clevis formed at the other end thereof, a lever fulcrumed in said clevis, a plunger in said body portion adapted to be actuated by said lever, a pair of reciprocating jaws in said body adapted to hold a rivet and to be actuated by said plunger, an anvil piece secured to said body below and in alignment with said jaws and said plunger against which said rivet 60 can be driven.

12. In a riveting machine, adapted to work on heavy materials, the combination of a body portion having a handle formed at one end thereof and an angularly disposed clevis formed at the other end thereof, a lever fulcrumed in said clevis, a plunger in said body portion adapted to be actuated by said lever, a pair of reciprocating jaws in said body adapted to hold a rivet and to be actuated by said plunger, said plunger having 70 75

a reduced head, said reduced head having a centrally disposed teat on its end, said teat being adapted to engage a recess formed in the head of said rivet.

- 5 13. A portable riveting machine, adapted to be used on heavy materials, which comprises a body portion having a handle formed integral therewith, a movable lever having its fulcrum on said body, said handle and said lever being adapted 10 to be gripped in one hand, a plunger actuated by said lever, and a pair of reciprocating jaws adapted to hold a rivet and to be actuated by said plunger.

14. A portable riveting machine, which comprises a body portion, and a handle formed there-

on, an actuating lever pivoted to said body, said handle and said lever being adapted to be gripped in one hand, a plunger actuated by said lever, a pair of reciprocating jaws, a rivet magazine secured to said body, said magazine having a feed slot in alignment with a recess formed in said jaws when said jaws are in their position of rest, said jaws and said plunger co-acting to successively receive and transport rivets from said rivet magazine to the material to be riveted, 10 means for releasing said rivets from said jaws, and means for clinching said rivets after being so released.

ROXTON C. MCKINNIE.
